UNITED STATES PATENT OFFICE.

JACOB FEDERHEN, OF BOSTON, MASSACHUSETTS.

IMPROVEMENT IN CROQUET-BOARDS.

Specification forming part of Letters Patent No. **59,376**, dated November 6, 1866.

To all whom it may concern:

Be it known that I, JACOB FEDERHEN, of Boston, Suffolk county, State of Massachusetts, have invented a new and useful Improvement in Croquet-Boards; and I do hereby declare that the following is a full, clear, and exact description thereof, which will enable others skilled in the art to make and use the same, reference being had to the accompanying drawing, forming part of this specification.

The present invention relates to the cushions of croquet-boards, or boards upon which the game of croquet is played; and it consists in forming such cushions of a string or strings of cat-gut, so called, such as is used for harps, violins, or other similar musical instruments, which cat-gut string passes around suitable stanchions or posts at each corner of the table or board, and is drawn with sufficient tightness, that, as the balls used in playing the game strike against it they will rebound therefrom.

In accompanying plate my improvement is illustrated, the figure being a perspective view of a croquet-board with it applied thereto.

A in the drawings represents a croquet-board, which in every particular, except so far as the present invention extends, is to be made in a substantially similar manner to the ordinary croquet-boards, but which in the present instance is provided with a cushion entirely around the same formed of a cat-gut string, B, that at each corner C of the board passes through the eye D of suitable fixed stanchions or posts E thereat, and is then drawn sufficiently tight to produce or cause the rebound of the balls used in the playing of croquet therefrom, as they are impelled or strike against the same, this cat-gut string when struck by the balls producing a sound or tone that greatly tends to impart life, vivacity, and enjoyment to the game.

I claim as new and desire to secure by Letters Patent—

Forming the cushion for a croquet-board of one or more cat-gut strings, substantially as and for the purpose described.

JACOB FEDERHEN.
